UNITED STATES PATENT OFFICE.

WILLIAM E. GORTON, OF ST. JOSEPH, MISSOURI.

DESIGN FOR A PUMP-CASING.

46,336.

Specification for Design.

Patented Sept. 1, 1914.

Application filed July 8, 1914. Serial No. 849,855. Term of patent 7 years.

To all whom it may concern:

Be it known that I, WILLIAM E. GORTON, a citizen of the United States, residing at St. Joseph, in the county of Buchanan and State of Missouri, have invented a new, original, and ornamental Design for Pump-Casings, of which the following is a specification, reference being had to the accompanying drawing, forming part thereof.

The figure is a perspective view of the pump casing.

I claim:

The ornamental design for a pump casing, as shown.

WILLIAM E. GORTON.

Witnesses:

WILLIAM F. HOFFMAN,

FRANK DUPREE.
